KNIFE SHARPENING MECHANISM

Frederick G. Clark, Buffalo, N. Y., assignor to
Eastman Machine Company, Buffalo, N. Y.

Application September 5, 1950, Serial No. 183,182

6 Claims. (Cl. 51—246)

1

This invention relates to knife sharpening mechanisms for cutting machines of the type commonly used for cutting cloth and other sheet materials, such as disclosed in my co-pending application No. 779,622, filed October 13, 1947, now Patent No. 2,537,208, dated January 9, 1951.

One of the objects of this invention is to provide a knife sharpening mechanism having means of improved construction for actuating the carriage on which the grinding means are mounted.

A further object is to provide improved presser foot locking mechanism for holding the presser foot of the cutting machine in such a manner that no damage will result to the grinding mechanism or the presser foot if the same is not lowered before starting the knife sharpening mechanism.

A further object is to provide a mechanism for releasably holding the presser foot against upward movement from any lowered position in which it cooperates with the material which is being cut, but which permits the same to be freely moved downwardly, for example, by the grinding carriage.

Other objects and advantages will be apparent from the following description of some embodiments of the invention, and the novel features will be particularly pointed out hereinafter in connection with the appended claims.

In the accompanying drawings:

Fig. 1 is a side elevation, partly broken away, of a cloth cutting machine equipped with automatic knife sharpening mechanism embodying this invention and showing the position of the parts when the sharpening mechanism is out of action and with the grinding means in their initial, uppermost position.

Fig. 2 is a fragmentary sectional elevation on an enlarged scale on line 2—2, Fig. 1.

Fig. 3 is a transverse, sectional view thereof on line 3—3, Fig. 2.

Fig. 4 is a fragmentary front elevation of the machine as seen from the front thereof, partly in section, and on a still larger scale.

Fig. 5 is a fragmentary, sectional view thereof on line 5—5, Fig. 4.

Fig. 6 is a fragmentary front elevation thereof, similar to Fig. 4, showing the parts in different positions.

Figs. 7 and 8 are fragmentary, sectional views thereof, respectively on lines 7—7 and 8—8, Fig. 6.

Fig. 9 is a fragmentary elevation thereof taken generally along line 9—9, Fig. 10, showing the presser foot locking mechanism.

2

Fig. 10 is a fragmentary side elevation thereof.

Fig. 11 is a fragmentary sectional elevation thereof on line 11—11, Fig. 9.

Fig. 12 is a fragmentary sectional view thereof on line 12—12, Fig. 11.

The cutting machine and its knife sharpening mechanism, except as hereinafter described, may be of known or other suitable construction. As herein disclosed, the machine comprises the usual base 20 adapted to rest and be moved about on the supporting table for the lay of material to be cut; an upright, slender standard 21 rigidly secured on and rising from the base and supporting the stationary frame or portion 22 of the electric motor which reciprocates the knife 23 in a vertical guide at the front of the standard through suitable drive mechanism including a crank or flywheel 24 on the front end of the horizontal rotor shaft of the motor, and which is suitably connected, for example, by means of a pitman and crosshead (not shown) to the upper end of the knife. The machine also includes a presser foot 26 on the lower end of a guard bar 27 which extends vertically in front of the knife and is suitably mounted for vertical adjustment on the machine to set the presser foot at different levels according to the thicknesses of different lays or piles of material.

In the machine as illustrated in the drawings, the knife is sharpened by grinding means of known type comprising two narrow abrasive belts or bands 30 and 31 which are disposed at opposite sides of the knife to travel crosswise of the knife in sharpening contact with opposite sides of the knife edge, around front drive pulleys 32 and 33 and rear, spring-actuated, belt-tensioning pulleys 34 and 35, the belts being power driven by the knife operating motor. The pulleys for the grinding belts are carried on the under side of a carriage 36 arranged to move or travel up and down lengthwise of the knife edge to enable the belts to sharpen the knife edge throughout its full length. The grinding belts or elements together with their driving mechanism and other parts of the sharpening mechanism may be mounted on a supporting housing or cover piece 38 which is stationarily but removably secured in place on the motor frame 22 at the front of the machine and serves to conceal the crank wheel 24 and other parts of the knife operating and sharpening mechanisms. The grinder carriage may be mounted and guided in its up and down movements and the grinding belt means constructed and mounted on the carriage in any suitable or customary manner, for example, as more fully described in Patent

#2,183,786, issued December 19, 1939, to Eastman Machine Company, assignee. While the sharpening mechanism of this invention preferably employs flexible belt grinding means, such as disclosed, the invention is not limited thereto and different grinding elements or means may be employed.

The drive mechanism for the grinding belts or elements, as shown in the drawings, is constructed as follows: The belt drive pulleys 32 and 33 are fixed on the lower ends of two vertical shafts 40 and 41 which rotate but are held from axial movement in suitable bearings on carriage 36, so as to move up and down with the carriage. Said shafts extend up into the housing or cover piece 38 and are movable axially through, but caused to rotate with intermeshing pinions 42 and 43, Figs. 2 and 3, which are held from axial movement in suitable bearings in the lower end of housing 38 and are oppositely rotated by a pinion 44 on the lower end of a vertical shaft 45, rotatable in suitable bearings in the housing. A spiral gear train 46, 47, 48 operatively connects the upper portion of shaft 45 with the shaft of a wheel 49, which is adapted to be moved into and out of contact with crank wheel 24 to be driven thereby. For this purpose, the shaft 50 of wheel 49 may be rotatably supported in a bearing in a bell crank lever 51 pivoted on a stud 52, shown in broken lines in Figs. 2, 4 and 6, which is fixed in housing 38 and forms the axle for the idler spiral gear 47. A spring 53, Figs. 2 and 4, acting between one arm of lever 51 and an opposing portion of housing 38, tends to swing said lever about its pivot to press wheel 49 with a frictional tire or peripheral band thereon into contact with the crank wheel 24, whereby when wheel 49 is pressed against the crank wheel 24, it is driven, and through the described gear trains, shafts and pulleys, drives the grinding belts 30 and 31.

The belt pulley shafts 40 and 41 are preferably of square or non-circular shape in cross section and slidably engage in correspondingly shaped axial holes in their driving pinions 42, 43, and each shaft is held in intended axial position from whipping or lateral motion by a cylindrical bushing 55, one of which is shown in Fig. 4. Each bushing is secured on the upper end of its shaft and is arranged to revolve and slide axially in a vertical guide tube 56 suitably mounted stationarily in housing 38. This arrangement provides much more durable connections between the pulley shafts and their driving pinions, and is more economical to produce than the usual splined arrangement of pinions on shafts, as by means of keys in the pinions slidably engaging in longitudinal keyways in the shafts.

An arm of lever 51 is pressed by spring 53 toward the upper end of a push rod 57 which is slidable vertically in suitable guide bearings 58 in housing 38 with its lower end projecting below the housing in position to be engaged by grinder carriage 36. When the grinder carriage is moved to its upper, initial position, it raises push rod 57 and shifts lever 51 against the action of the spring 53 to move and hold driven wheel 49 out of contact with crank wheel 24, thus stopping operation of the sharpening mechanism. When the sharpening mechanism is started to sharpen the knife, the grinder carriage is lowered, as later explained, and permits push rod 57 to descend and allow driving engagement of wheel 49 with the crank wheel, as shown in Fig. 2.

The traversing mechanism for producing the

up and down or to and fro travel of the grinder carriage 36 and grinding elements or belts along the knife edge is preferably constructed as follows: 60 represents a screw shaft, having crossing right and left hand screw threads. This screw shaft may be rotated in any suitable manner, and in the construction shown, the rotating means therefor are located in the grinder carriage 36. In this construction the lower end of the screw shaft is journalled to rotate in the grinder carriage and held against axial movement relatively to the carriage by thrust collars 61 and 61a, Fig. 6. A part of the lower end of the screw shaft is of a square or non-circular cross section to extend through a similarly shaped base in a gear 62 which meshes with a pinion 63 secured on an idler shaft 64 on which a larger gear 65 is also secured. The larger gear meshes with a gear 66 mounted on the belt pulley shaft 41. Consequently, as the shaft 41 is rotated through the mechanism described, the screw shaft 60 is turned through the speed reducing gear train 62, 63, 65 and 66, when the sharpening mechanism is in operation for driving the grinding belts.

The screw shaft 60 extends vertically up through the housing 38 and passes through two nuts 67 and 68, one of these nuts having a left hand thread engaging the left hand thread of a shaft, and the other nut having a right hand thread engaging the right hand thread of the shaft. These nuts are held from axial movement relatively to the screw shaft between suitable bearings in the housing member 38, and preferably an anti-friction bearing 69 extends about the screw shaft between the adjacent inner ends of the nuts. By holding one of the nuts 67 or 68 from rotation while leaving the other nut free to rotate, the screw shaft rotating in the stationary nut is moved axially upwardly or downwardly. In the construction shown, when the lower nut 67 is held against rotation, the screw shaft moves downwardly, and when the nut 68 is held, the screw shaft is moved axially upwardly. When both nuts are left free to rotate, there is no endwise movement of the screw shaft.

Suitable mechanism is provided for holding and freeing the nuts, and in the construction shown by way of example for this purpose, a latch member or element 70 is provided which is mounted to swing about a pivot 71 secured in a part of the housing 38. This latch is provided with a dog or detent 72 which, when the dog is swung into the position shown in Fig. 4, will extend into the path of rotation of wings 73 extending outwardly from the nut 67. The latch also has another dog or detent 74 which extends into position to engage wings or projections 75 on the nut 68 when the latch is swung into the position shown in Fig. 6. Obviously, when one dog or detent is in position to engage the wings of one of the nuts, the other dog will be out of the path of rotation of the wings of the other nut.

77 represents a spring having one end thereof secured to the fixed pivot 71 and the other end to the latch 70 and disposed to yieldingly urge the latch 70 in the position shown in Fig. 6, in which the dog or detent 74 is in position to hold the nut 68 against rotation.

The latch 70 may be swung about its pivot against the action of the spring 77 by means of a link 79 pivoted at 80 to the latch 70 and having a handle 81 at the upper portion thereof. The link 79 is guided in its movement by means of a

pin 82 secured to the housing 38 and extending through a guide slot 83. A latch holding member 84 is provided which is pivoted at 85 on a fixed part of the housing 38 and which has an arm 86 extending into position to engage a shoulder 87 on the latch 70. Consequently, when the handle 81 is pushed downwardly, the link 79 will swing the latch 70 into the position shown in Fig. 4, in which position the arm 86 will move into engagement with the shoulder 87 of the latch and hold the latch in position to hold the nut 67 against rotation, thus effecting downward movement of the screw shaft and the grinder carriage connected thereto. To ensure the swinging of the holding member 84, a spring 89 is provided, one end of which seats against a part fixed to the housing 38 and the other end of which engages an arm 90 of the holding member. The spring 89, in the particular construction shown by way of example, is in the form of a coil spring extending about the screw shaft 60.

In order to start the sharpening mechanism, the starting handle 81 is pushed downwardly, which causes the latch 70 to swing from the position shown in Fig. 6 into the position shown in Fig. 4, for interrupting rotation of the lower nut 67. During this movement of the latch 70, there is a neutral position in which both of the dogs 72 and 74 are disengaged from both of the nuts 67 and 68, leaving both nuts free to rotate. This permits the spring 53 to actuate the bell crank lever 51 to force the driven wheel 49 into contact with the crank wheel 24 and, consequently, through the gearing described, the screw shaft 60 will be rotated. The spring 53 will be free to swing the bell crank lever 51 for the reason that the push rod 57 will no longer be held in its upper position by the carriage 36, and this spring also moves the push rod 57 down to start downward movement of the carriage 36. Further movement of the latch 70 from its neutral position into position to engage a wing 73 of the lower nut 67 and thereby stopping its rotation, will cause downward travel of the screw shaft and the grinder carriage 36. The latch 70 will be held in the position shown in Fig. 4 by means of the holding member 84, as described. The downward movement of the screw shaft will continue until the latch 70 is moved back from the position shown in Fig. 4 to that shown in Fig. 6.

The upper end of the screw shaft 60 is provided with a reversing member or sleeve 93 which is slidable in a guide tube 94 into which the screw shaft 60 extends. The reversing member or sleeve is preferably adjustably mounted on the upper end of the screw shaft in any suitable manner and, in the construction shown, the screw shaft is provided at its upper end with a threaded stud or extension 95 having a threaded engagement with the reversing member or sleeve 93, and a lock nut 96 is provided for securing the reversing sleeve in the desired position. As shown in Fig. 6, as the screw shaft moves into the lower portion of its stroke, the reversing member or sleeve 93 engages the spring pressed arm 90 of the holding member and thus causes the holding member to swing about its pivot 85, so that the arm 86 thereof will disengage the shoulder 87 of the latch 70. When this happens, the spring 71 will return the latch from the position shown in Fig. 4 to that shown in Fig. 6, thus disengaging the lower nut 67 and holding the upper nut 68 against rotation. This will cause the screw shaft 60 to move upwardly, thus moving the grinder carriage 36 upwardly. The upward

movement of the grinder carriage is stopped when a portion of this carriage engages the push rod 57, which swings the bell crank lever 51 about its pivot 52 against the action of the spring 53, and thus moves the driven wheel 49 out of contact with the crank wheel 24, thus stopping the operation of the sharpening mechanism and holding the carriage 36 in its upper position. The push rod 57 will thus be held in engagement with the bell crank lever 51 and, consequently, the sharpening mechanism will be held in its upper and inoperative position until the handle 81 is again actuated by the operator.

In order to avoid the possibility of damage to the machine in the event that the operator holds the handle 81 in its lower position when the mechanism is about to begin to raise the grinder carriage, a pin 98 is provided on the link 79, which pin is located in the path of movement of the holding member 84 as it swings out of position to engage the shoulder 87 of the latch 70. Consequently, the positive swinging of the holding member 84 by means of the reversing sleeve 93 will force the link 79 upwardly so that the latch 70 will disengage the wings of the lower nut 67. Preferably, the holding member 84 is provided with an arm 99 which extends outwardly in position to be actuated by the operator and by means of which the holding member may be moved out of engagement with the latch 70.

The reversing sleeve 93 is axially adjustable on screw shaft 60, as by screwing the same on the reduced, threaded upper end of the shaft and fixing it in adjusted position, as by a lock nut 96, so that by appropriate adjustment of this sleeve, or by using sleeves of different lengths on the screw shaft, the extent of downward travel of the grinding means may be increased or decreased, as may be necessary for grinding the full length of the edge of a knife of one or another length or which may have a reciprocating stroke of one or another length. It is usual in cutting machines of the type disclosed herein to change the length of stroke of the reciprocating knife as most suitable for cutting materials of different character. Also such machines are made so that the machine may be provided with a standard of one or another length and with a knife of appropriate length, to better adapt the machine for cutting material piles or lays of different heights. By using a reversing sleeve such as described, of appropriate length, or by appropriately adjusting the sleeve axially to different positions on the screw shaft, very simple and efficient means are provided for causing the return or upward travel of the grinding means when, in its downward travel, it has reached the lower end of the knife, regardless of the length of the knife or the length of the reciprocating strokes of the knife. Furthermore, the reversing sleeve being cylindrical and rotatable and movable axially in a guide tube 94, effectually holds the upper end of the screw shaft from whipping or lateral motion during the operation of the sharpening mechanism.

Since the presser foot 26 is necessarily located in the path of movement of the grinder carriage 36, it is necessary to provide means whereby damage to the machine is avoided in case the sharpening mechanism is actuated before the presser foot has been moved to its lowest position. In the construction illustrated, this is accomplished by providing a mounting for the presser foot by means of which the presser foot rod or guard bar 27 may be locked against upward movement

by the goods which are being cut, but is free to move downwardly if engaged by the downwardly moving grinder carriage.

In the construction shown for this purpose, see Figs. 9-12, a cam member or arm 105 is provided, the outer end of which is shaped to cooperate with the presser foot rod 27 which, in the construction shown, is square in cross section. This cam member or arm 105 is pivoted on the frame of the machine and biased to move into an inclined position, as shown in Fig. 11, in which the arm extends downwardly at a slight inclination from its pivot to the rod 27. The outer end of the arm is notched or recessed to engage the foot rod 27. It will be obvious that when the arm 105 is in the position shown in Fig. 11, upward movement of the rod 27 is prevented while downwardly movement is not materially resisted by means of the arm 105. Consequently, when the presser foot is engaged by the downwardly moving grinder carriage, this carriage will move the presser foot and its guide rod 27 downwardly. The arm 105, however, by a camming action prevents upward movement of the presser foot and its rod 27 by the goods which are being cut. In adjusting the presser foot into proper relation to such goods the same may be moved downwardly manually to the correct position. In order to effect upward movement, however, it is necessary to swing the arm 105 out of engagement with the presser foot rod 27.

The mechanism for effecting these results may be constructed in any suitable or desired manner. In the construction illustrated by way of example, the arm 105 is formed by the end portions of two metal pieces or strips bent into approximately Z-shape, one end of each strip being secured to a corresponding end of the other strip to form the arm 105, the ends of the strips being bevelled to form a notch or recess which cooperates with two adjacent sides of the square presser foot rod shown by way of example in the drawings. The opposite ends of the two strips are spaced from each other and bent to extend substantially parallel to the arm 105 and are provided with suitable stub shafts or trunnions 107 and 108 rigidly secured thereto and journaled in suitable bearings in the frame member 38 of the machine. One of the strips is provided with an outwardly extending arm 109 to which one end of a coil spring 110 is attached, the other end of this spring being secured to the frame of the machine. This spring exerts pressure on the arm 109 to swing the other arm or cam member 105 into engagement with the presser foot rod. The spring 110 is preferably coiled about a bushing or sleeve 111 through which the shaft 108 extends.

The movement of the arm 105 out of engagement with the presser foot rod may be effected in any suitable or desired manner, and, in the construction shown, a bevel gear 114 is secured to the end of the shaft 108 and meshes with another bevel gear 115 secured on a rod or shaft 116 which forms a part of a crank handle 117 which extends outwardly from the machine into a position convenient to the operator. Consequently, when the operator swings the crank arm 107 in a clockwise direction in Fig. 9, the shafts 107 and 108 will be turned to swing the arm 105 secured thereto in a clockwise direction in Fig. 11, out of engagement with the presser foot rod, so that the presser foot may be adjusted relatively to the material to be cut. If desired, another spring 118 may be provided which acts

on the shaft 116 to cooperate with the spring 110 to return the handle to normal position, in which the presser foot rod is locked against upward movement. Any other means for actuating the arm or cam member 105 may be provided.

It will be understood that various changes in the details, materials and arrangements of parts which have been herein described and illustrated in order to explain the nature of the invention, may be made by those skilled in the art within the principle and scope of the invention, as expressed in the appended claims.

I claim as my invention:

1. In a knife sharpening mechanism for cutting machines having a knife, driven grinding means for the knife edge mounted on a movable supporting carriage movable to and fro along the knife edge by a rotatable and axially movable screw shaft having right and left hand threads, and a pair of nuts held from axial movement and operatively engaging respectively the right and left hand threads of said shaft, that improvement which includes a latch member pivotally mounted on the cutting machine and having a pair of detents mounted in spaced relation on said latch, said latch member when swung into one position moving one of said detents into position to hold one of said nuts against turning and releasing the other detent from the other nut, and when swung into another position releasing said first detent from said first nut and swinging said other detent into holding engagement with said other nut, said first nut when held against rotation causing said screw shaft to move said grinding means in one direction lengthwise of said knife and said other nut when held against rotation causing said screw shaft to return said grinding means to its initial position, said latch member being movable manually in one direction to move said first detent to engage said first nut, a holding member for holding said latch in said last mentioned position, resilient means for urging said latch member to swing about its pivot into engagement with the other of said nuts when said holding member releases said latch, and means actuated by the movement of said screw shaft in said first mentioned direction for releasing said holding member to permit said yielding means to swing said latch member into position, to reverse the movement of said screw shaft.

2. A knife sharpening mechanism according to claim 1, characterized in that said screw shaft has a part mounted thereon which engages said holding member to move the same into position to release said latch when said screw shaft has completed its downward motion.

3. A knife sharpening mechanism according to claim 1, and including a link connected with said latch and movable manually to swing said latch into position to effect downward movement of said screw shaft.

4. A knife sharpening mechanism according to claim 1, and including a link connected with said latch and movable manually to swing said latch into position to effect downward movement of said screw shaft, and a part on said link extending into a position to be engaged by said holding member when the same is moved into latch releasing position to positively move said link into position to permit said yielding means to move said latch member into position to engage said other nut for moving said screw shaft in a reverse direction.

5. In a knife sharpening mechanism for cutting machines having a knife, driven grinding

means for sharpening the knife edge, a movable supporting carriage for the grinding means, a presser foot for the work and a presser foot rod adjustable on said machine to change the position of the presser foot relatively to the work, that improvement which includes an arm pivoted on the machine, yielding means for urging said arm into a position in which the outer end of said arm engages said presser foot rod while extending downwardly from said pivot into engagement with said rod to prevent upward movement of said rod and permitting downward movement of said rod when said presser foot is

engaged by said carriage, and means extending into a position accessible to the operator for swinging said arm into position to release said presser foot rod.

5 6. A knife sharpening mechanism according to claim 5 and including a shaft on which said arm is mounted, and means connected with said shaft for turning the same against the action of said yielding means for swinging said arm out of engagement with said presser foot rod.

FREDERICK G. CLARK.
